UNITED STATES PATENT OFFICE.

THOMAS G. BRITTON, OF LOUISVILLE, NEBRASKA.

BOILER.

SPECIFICATION forming part of Letters Patent No. 596,979, dated January 11, 1898.

Application filed December 31, 1896. Serial No. 617,586. (No model.)

To all whom it may concern:

Be it known that I, THOMAS G. BRITTON, a citizen of the United States, residing at Louisville, in the county of Cass and State of Nebraska, have invented certain new and useful Improvements in Boilers; and I do hereby declare the following to be a full, clear, and exact description of the invention, such as will enable others skilled in the art to which it appertains to make and use the same.

My invention relates to improvements in boilers, and has for its object the production of a device of this class in which the water is brought into direct contact with the products of combustion and, after being converted into steam, is mixed with the gases liberated by combustion and is directed to an engine or other device for the conversion of its potential energy into kinetic power.

To the accomplishment of the foregoing object my invention consists in providing a combustion-chamber upon the interior of a boiler and in directing the gas liberated by combustion within the chamber to the interior of the boiler below the surface of the water and in certain other novel features subordinate to the general arrangements specified and hereinafter described.

Referring to the drawings, Figure 1 is a central longitudinal view of my device complete, and Fig. 2 is a central longitudinal section through the boiler thrown into perspective and showing the mechanism upon the interior of the boiler in perspective.

Referring to the numerals on the drawings, 1 indicates a horizontal cylindrical boiler provided with a steam-dome 2 and a safety or pop valve 3, as usual.

4 indicates the feed-water pipe communicating with the boiler, preferably adjacent to its bottom, and 5 the feed-pipe leading from the dome 2 to an engine or other similar device. (Not illustrated.) Within the boiler and preferably near its bottom I provide a comparatively long cylindrical combustion-chamber 6 of considerably less diameter than the diameter of the boiler and extending from its front end 7 to a point adjacent to its rear end 8.

9 indicates an enlarged air-pipe piercing the front end of the boiler and communicating with the interior of the combustion-cham-

ber and preferably provided with a hinged cap 10 and having suitable connection through an air-tube 11 with a source of compressed air. (Not illustrated.) I prefer to employ an air-pump designed to supply air under pressure to the interior of the combustion-chamber.

12 indicates a fuel-pipe leading into the combustion-chamber, preferably at a point immediately above the air-pump 9, and connected with a convenient source of oil, gas, vapor, or other fuel supply.

13 13 indicate a pair of what I will call "injector-pipes," extending along either side of the exterior of the combustion-chamber, having their front ends closed, as by caps 14, and connected at their rear ends by a transverse pipe 15, communicating with a depending pipe 16, controlled at its point of connection with the transverse pipe 15 by a check-valve 17, as illustrated.

18 indicates the injector supply-pipe piercing the rear end or head of the combustion-chamber and communicating with the depending pipe 16, the injector supply-pipe being controlled by an injector supply-valve 19, operated by a hand-wheel 20 upon the exterior of the head 8 of the boiler and connected to the valve, as by a screw 21.

The valves 17 and 19 are preferably hollow, as illustrated, for the purpose of permitting the water within the boiler to fill their interior and prevent their burning out when subjected to high temperature.

22 indicates an escape-pipe piercing the top of the combustion-chamber, preferably near its rear end, and extending upwardly through the boiler, above which it is provided with a safety-valve 23 and with an escape-valve 24, controlled by hand-wheel 25.

The water within the boiler having been raised to a sufficient level to completely envelop the combustion-chamber 6, the cap 10 is opened and the fuel emitted from the pipe 12 is ignited, access to the interior of the combustion-chamber for this purpose being had through the air-pipe 9. The cap 10 is then closed and securely locked, and the fuel and air are fed under suitable pressure to the interior of the combustion-chamber. The temperature of the chamber 6 will be raised and will heat the water within the boiler suffi-

ciently to generate steam; but in order to assist further in such generation and to charge the steam with expansible gases the cock 20 is opened, and the gases liberated within the 5 combustion-chamber escape into the injector-tubes 13, whence they are injected into the body of water at a pressure sufficiently high to prevent the entrance of water from the boiler through the apertures in the injector-tubes.

In order that the air and fuel supply will be coincident, any suitable mechanism may be provided for automatically cutting off the fuel-supply when the air-supply ceases, or vice versa, and I have illustrated and described one form of mechanism for accomplishing this result.

26 indicates a valve in the air-tube 11, controlled as by a hand-wheel 27 and having its 20 spindle or plug independently connected with the spindle or plug of a valve 28 in the fuel-pipe 12, as by a lever-and-link connection illustrated and well known in the art.

It will be observed that the fuel and air must be forced into the combustion-chamber under a pressure in excess of the internal pressure of the combustion-chamber and that the gases injected into the water of the boiler must be under a higher pressure than that within the 30 interior of the boiler.

By means of the construction and arrangement described I am enabled to generate steam within a boiler by direct contact between the water and combustion-chamber and am at the same time enabled to inject into the 35 body of water expansible gases which when commingled with the steam serve to augment its potential energy.

I do not desire to limit myself to the details 40 of construction herein shown and described, but reserve to myself the right to change, modify, or vary them at will within the scope of my invention, as it is evident that various 45 modifications might be made with practical results, the essential characteristics being, first, the injection of expansible gases into the boiler from the combustion-chamber, and, second, in locating the combustion-chamber in the boiler, and in certain other peculiarities of construction and arrangement not necessary to be mentioned in detail.

I claim—

1. The combination with a boiler and combustion-chamber therein, of means for supplying fuel under pressure to the combustion-chamber, a valve-controlled escape-pipe communicating with the said combustion-chamber and extending to the exterior of the boiler,

and a plurality of valve-controlled injector-tubes extending longitudinally within the 60 boiler and provided with perforations through their under sides exclusively, whereby the gases injected into the contained water will be forced to penetrate to the bottom of the boiler before escaping to the steam-space at 65 its top, substantially as specified.

2. The combination with a boiler and combustion-chamber therein, of an oil-pipe and an air-pipe extending upon the exterior of the boiler and communicating with the combustion-chamber, interdependent valves in said pipes, a plurality of perforated injector-tubes extending longitudinally with respect to the boiler and communicating with one end of the combustion-chamber, a valve controlling 75 the said tubes, and a check-valve intermediate of the injector-tubes and controlling-valves, substantially as specified.

3. The combination with a boiler and combustion-chamber therein, and perforated 80 valve-controlled injector-tubes communicating with the combustion-chamber, of an enlarged air-pipe piercing the front of the boiler and communicating with the interior of the combustion-chamber, a hinged cap closing the 85 end of said air-pipe, an oil-supply pipe communicating with the combustion-chamber from the exterior of the boiler, an air-supply pipe communicating with the enlarged air-pipe, and interdependent valves in the air-pipe and oil-pipe respectively, substantially 90 as specified.

4. The combination with a boiler, and a combustion-chamber therein, of perforated injector-tubes extending from one end to the 95 other of the combustion-chamber and adjacent to its top, an injector supply-pipe piercing the rear end of the combustion-chamber and provided with a controlling-valve, a valve-controlled pipe extending at right angles to the injector supply-pipe and communicating at its upper extremity with each of the injector-tubes respectively, air and fuel pipes piercing the opposite end of the combustion-chamber and extending upon the out-side of the boiler, means for supplying air and fuel under pressure to said last-named pipes and interdependent valve located in 100 said pipes, substantially as described.

In testimony whereof I have signed this 110 specification in the presence of two subscribing witnesses.

THOMAS G. BRITTON.
